UNITED STATES PATENT OFFICE.

ADOLPH WEISMAN, OF BROOKLYN, NEW YORK.

METHOD OF MANUFACTURING METAL BEDS.

Original application filed August 22, 1924, Serial No. 733,520. Divided and this application filed March 14, 1925. Serial No. 15,608.

The present invention is primarily concerned with the method of making metal beds of the character disclosed in my copending application, Serial No. 733,520 filed 5 August 22, 1924, and since issued as Patent No. 1,563,002 on November 24th, 1925, of which the present application is a division.

When a metal bedstead is provided with square or other tubing of substantial transverse dimensions extending about the periphery of the end panels to frame or bind the latter, it lacks the desired characteristic appearance of a wooden bed of modern design, the end panel of which is of substantial 15 thickness and devoid of any thick bordering bead structure.

The bed disclosed in the copending case above identified includes hollow panels which consist of two relatively thin sheets of bendable metal having their edges turned over and welded together so as to eliminate the usual bead, affording panels of uniform thickness to closely simulate the appearance of a wooden bed end.

25 The present invention relates particularly to the novel method used in manufacturing the panels, particularly the method by which I form hollow wing panels to supplement the head and foot boards, such wing panels being of transverse curvature and having preferably a compoundly curved upper edge. The method preferably consists in bending the two panel sheets to conform to a curved template turning the edges of the sheets over the edge of the template, hammering down the turned over edges to render the excess metal inconspicuous, welding the edges together and polishing off the weld to render the same practically unnoticeable.

30 The invention may be better understood from the following description in connection with the accompanying drawings, wherein—

Figure 1 is a fragmentary perspective view of the bed;

Figure 2 is a vertical sectional view on the line 2—2 of Figure 1;

Figure 3 is a transverse sectional view on the line 3—3 of Figure 1;

Figure 4 is a side view of one of the hollow 45 posts;

Figure 5 is a perspective view showing a formed wing panel being removed from its template.

Wooden bedsteads of conventional and 50 modern design are formed with end panels

which usually consist in a single wooden slab relatively heavy and presenting an untrimmed, unbordered curving upper edge which heretofore has never been successfully simulated by metal bed manufacturers.

The present invention has to do primarily with the construction of the two end pieces, namely the head piece and the foot piece of a metal bed and for purposes of illustration, I have shown merely a single end piece which for convenience of description, may be considered as an upright foot piece. The construction of the head piece would be substantially the same except the head pieces are made slightly higher.

The foot piece end of the bed includes a pair of hollow legs 10, 10 mounting between them a hollow metallic panel 11 which constitutes the foot board. The foot board may be supplemented by the use of a pair of rearwardly curving wing portions 12 and in the event the latter are used, legs 13, 13 would be employed to assist the legs 10 in supporting them.

The present invention resides primarily in the novel method of forming these three panels. In forming the foot board panel I take a pair of metallic sheets 11^a, 11^b of approximately similar size and of the correct shape and interpose between them, a flat template 85 having an upper edge of the general curvature indicated in the drawings. The side edges of the sheet 11^a are folded around the side edges of the template into abutting relationship with the flat face of the sheet 11^b 90 thereby forming spacer flanges 14. The upper edges of both sheets are folded over the curved edge of the template, hammered down and welded together at 15 along the median line of the template edge. This operation 95 leaves the lateral edges of the sheet 11^b extending beyond the turned in edges of the other sheet as indicated at 16. The template may be removed through the open bottom of the panel and the panel joined to the legs 100 13 by forcing the edges of the former into the longitudinal slots 17 in the legs. Preferably the panels are also welded at 18 to the legs to strengthen this frictional union.

For closing the open lower end of the panel, I may employ a closure strip 19 formed at opposite edges with turned over beads 21 which may embrace and be welded at 20 to the lower ends of the plates 11^a, 11^b. The beads of the closure strip enter 110

notches 21^a in the posts and at the edges of the slot 17. If desired, a hollow transverse apron 26 fitting snugly against the under face of closure strip 19 may connect the legs 5 immediately below the panel and serve an additional strengthening brace. The turned over edges 27 of the plates forming the apron may be overlapped if desired, but need not be welded since their union is ordinarily concealed.

The method of forming the curved panels for the end wings involves certain additional operations because of the longitudinal curvature of the template 22 on which they are 15 formed and the compound curvature of the upper edge of such template. The two plates or sheets of metal 12^a, 12^b, used in forming wing panels are cut to proper shape and then bent longitudinally by a hammering operation 20 in order to properly conform them with the longitudinal curvature of the template. The side edges of plate 12^a are bent around the edges of the template to define spacer flanges and the upper edges of both of the 25 sheets folded over the curved upper edge of the template. This folding operation is completed by a hammering operation using the template as an anvil and flattening out the turned over upper edges of the sheets in so 30 far as possible, so that the excess metal at the upper edges is in large measure concealed or rendered inconspicuous. The turned over upper edges of the sheets are then welded together in the manner above described and 35 the template withdrawn through the lower end of the panels. Supplemental closure strips 23 and aprons 24 similar to those associated with the main panel may be employed to finish the assembly and lend an attractive appearance to the bed. It will be 40 understood that the wing panels are frictionally fitted into slots in the supporting legs and soldered thereto as indicated at 25.

Both the foot board panel and the wing 45 panels may be embossed in any appropriate manner to enhance their attractive appearance and may be given a finish which will simulate the grain of an ordinary wooden panel.

50 My panel of double thickness is of sufficient strength to resist bending and is of a thickness which will correspond closely to the thickness of a wooden panel. The somewhat unsightly bead commonly employed at the upper edge of the panels and which is an unmistakable indication of the metallic nature of the bed is entirely eliminated. The lines of welding at the top of the panels may be finished and polished in 55 various well known ways so that they are quite inconspicuous. The double panels in themselves have a very desirable heat insulating effect which is particularly useful in case the bed is arranged so that one of its 60 ends is close to a window or radiator. This 65

heat insulating effect may be supplemented if desired by filling the hollow panels with an asbestos or similar heat insulating material.

It is quite obvious that the shapes, sizes, and curvatures of the panels are entirely optional with the manufacturer and that any shapes and forms demanded by the trade might be made in accordance with my improved process.

75 It will thus be seen that there is herein described a method in which the several features of this invention are embodied, and which attains the various objects of the invention and is well suited to meet the requirements of practical use.

80 As many changes could be made in the above method, and many apparently widely different embodiments of this invention could be made without departing from the scope thereof, it is intended that all matter contained in the above description or shown in the accompanying drawing shall be interpreted as illustrative and not in a limiting sense.

85 Having thus described my invention what I claim as new and desire to secure by Letters-Patent is:

1. The method of forming head and foot 90 board panels for metal beds which consists in interposing a template between two sheets of bendable metal, folding the edges of the sheets around three sides of the templates and joining certain of said edges together and then withdrawing the template through 95 the open side edge of the hollow panel thus formed.

100 2. The method of forming head and foot board panels for metal beds which consists in interposing a template between two sheets of bendable metal folding the side edges of one sheet around the template to form spacer flanges, folding the upper edges of both sheets around the edge of the template until they abut in edge to edge relationship, 105 welding said abutting edges, and withdrawing the template through the open bottom of the panel.

110 3. The method of forming foot board panels for metal beds which consists in interposing a longitudinally curved template having a curved upper edge between a pair of sheets of bendable metal, curved in accordance with the curvature of the template, folding the side edges of one sheet around the side edges of the template to form spacer flanges, folding the upper edges of the two sheets over the upper curved edges of the template, hammering such edges to conform 115 to the curvature of the edge of the template and welding the folded over portions of the sheets into a unitary structure.

120 4. The method of forming a sheet metal structure which consists in interposing a template having a curved edge between two 125

sheets of bendable material, folding the ends of the sheets upon the curved edge of the template joining said ends together and then withdrawing the template.

- 5 5. The method of forming a sheet metal structure which consists in bending two sheets of material to conform with opposite sides of a cylindrically curved template structure folding the end of the sheets inward against the compoundly curved end of

the template until they abut in edge to edge relationship, welding said abutting edges and withdrawing the template away from the welded edge for removal thereof from the open end of the structure opposite said 15 welded joint thereof.

Signed at New York, in the county of Kings and State of New York, this 9th day of March, A. D. 1925.

ADOLPH WEISMAN.
